UNITED STATES PATENT OFFICE.

ALBERT M. PIGEON, DECEASED, LATE OF NORRISTOWN, PENNSYLVANIA, BY ANNA M. PIGEON, ADMINISTRATRIX, OF NORRISTOWN, PENNSYLVANIA.

YARN-TENSIONING DEVICE.

Application filed December 19, 1923. Serial No. 681,573.

This invention relates to yarn tensioning devices for textile machinery, and its principal object is to provide a means adapted to yield automatically in response to variations in pull impressed upon the yarn so as to sustain the yarn under uniform tension at all times; in combination with a stabilizing means controlling operation of the drag impressing means, so as to retard responsive vibrations of the latter, whereby to aid in the production of a smooth even fabric.

In addition to the foregoing, this invention comprehends improvements in the details of construction and arrangement of the correlated parts to be hereinafter set forth and particularly pointed out by the appended claims.

In the accompanying drawings, Fig. I is a view in top plan of a yarn tension device constructed in accordance with this invention;

Fig. II is a view of the device in front elevation; and,

Fig. III is a view thereof in vertical section taken on the line III—III of Fig. II.

With reference to the drawings, 10 indicates a horizontal frame bar having an upwardly directed extension 11 by which the tension device may be supported from the frame of a fabric producing or sewing machine through the medium of a threaded fastening 12. A series of circumferentially grooved elements 13 are fixedly secured to one face of the frame bar 10 through the medium of screws 14, forming stationary yarn engaging elements for a purpose to be presently noted.

A pair of arms 15 forming part of the frame bar 10 are directed laterally to afford journal support for the ends of a shaft 16. The journalling of the shaft 16 is effected through the medium of pivot screws 17 which are adjustably supported in the ends of the arms 15, the screws being formed with pointed terminals 18, which enter correspondingly shaped recesses in the ends of the shaft 16 to afford frictionless bearings for the latter. The pivot screws 17 are fixed in adjusted position, by means of jamb nuts 19 threaded upon the same. Extending radially and horizontally from the shaft 16 and rigidly affixed thereto are a series of arms 20, each arm being positioned between an adjacent pair of the aforesaid grooved yarn engaging

elements 13, and one beyond each end element of said series. The terminals of the arms 20 are preferably looped to enclose yarn engaging elements in the form of eyelets 21 of a smooth, hard, wear resistant material such as porcelain. The frame bar 10 is formed with a depending extension 22 to the lower end of which there is pivotally connected the piston member 23 of a stabilizing or retarding device of the dash-pot type. This piston member 23 cooperates with the cylinder 24 of the dash-pot whose upper terminal is bifurcated to receive an extension 25 of one of the arms 20, said extension 25 being looped to receive a pin 26 which passes through the bifurcation and said loop to pivotally connect the parts together. A lever 27 is fixed to the shaft 16 and extends in an opposite direction with respect to the arms 20 and supports a sliding counterweight 28, which may be fixed in any adjusted position, by means of a set screw 29 entering the same and adapted to engage the lever 27. A constant drag-impressing instrumentality is provided in the form of a strand of wire 30 secured at one end to the extension 22 and bent to form a series of undulations 31 terminating in a loop which is designed to retain a guide eyelet 32. The yarn indicated at 33, in coming from the source of supply, passes through the stationary eyelet 32, then back and forth in and about the undulations 31, then from left to right through the several eyelets 21 of the movable yarn-engaging elements incidentally engaging the nether portions of the interposed fixed yarn-engaging elements 13, and after leaving the last of the eyelets 21 passes directly to the fabric producing means or sewing mechanism of the textile machine.

It will be apparent that during operation of the machine, a sluggishly responsive drag is impressed upon the yarn 33 by virtue of the counterweight 28, the influence whereof is exerted upon the extremities of the arms 20, thereby urging the latter upward and causing the yarn 33 to pass between the engaging elements 13 in a constantly reversing path. Hence, any variation in the linear traveling speed of the yarn 33 will effect vertical oscillation of the movable yarn engaging eyelets 21, yielding to downward movement as the pull on the yarn 33 or rate of travel is increased and taking up said

yarn as the rate of travel or amount of pull thereon decreases. It is desirable that such changes in the pull or rate of travel be responded to slowly and not abruptly, in order that the resultant product or fabric of the machine may be uniform and smooth in all its parts. To this end, the stabilizing device comprehended by the members 23 and 24 is provided to control vertical oscillation of the movable yarn engaging elements 20, 21, this action being occasioned by reason of the air which is confined within the cylinder 24, and which can only effect an exit when the cylinder space is decreased by flowing outward around the sides of the piston 23, and conversely by permitting air to enter said cylinder in the same manner when replacement occurs within the cylinder, by reason of the outward movement of the piston 23 during upward travel of the movable yarn engaging elements 21. The retarding influence of the dash-pot device hence causes the movable elements 20, 21 to respond in a very sluggish manner to vibrations imparted thereto by the pull on the yarn 33 during its passage. By shifting the counterweight 28, along its support, the device may be adjusted to provide a compensating drag for any kind of yarn employed, or to conform to any conditions depending upon the character of the machine with which the device is to be used, or the nature of the work produced. Thus the same device may be used for either silk, wool or cotton yarns, or yarns of various qualities, by properly adjusting the counterweight tension.

It has been found in practice that as a result of the use of the stabilizing device employed in connection with this invention, the tension is uniformly maintained with the result that a smooth even fabric is produced and when the device is used, for instance, on a knitting machine the needles are held in tension, thereby preventing formation of loose and tight stitches. Owing to its simplicity of construction, this improved tension device is not open to the objection of becoming suddenly disorganized or inoperative with proper usage. It is of course obvious that other forms of stabilizing means may be substituted for the dash-pot arrangement, and hence no limit is hereby involved to the specific use of the same, as

other well known retarding devices may be found equally suitable and convenient.

Having thus described the invention, what is claimed is:

1. In a yarn tensioning device comprising a stationary frame member with a group of spacedly aligned stationary yarn engaging elements and means exerting constant drag upon the yarn, the combination of a co-operating movable member including a shaft journaled in the frame member and having a series of projecting yarn engaging elements swingable in the intervals between the stationary elements aforesaid, an adjustable counterweight adapted to partially balance the yarn engaging elements and for imparting compensative drag, and a pneumatic stabilizer embodying a stationary and a movable member respectively pivoted to a depending extension of the frame member and to one of the movable yarn engaging elements aforesaid, said stabilizer functioning to render sluggish responsive movements to said movable members incident to spasmodic variations in the pull upon the yarn.

2. The combination in a yarn tensioning device of a stationary frame member having a group of spacedly aligned stationary yarn engaging elements, an undulated member exerting a constant drag upon the yarn, a movable member including a shaft journaled in the frame member and having a series of projecting yarn engaging elements swingable in the intervals between the stationary elements aforesaid, an adjustable counterweight adapted to partially balance the yarn engaging elements for imparting compensative drag, and a pneumatic stabilizer embodying a stationary and a movable member respectively pivoted to a depending extension of the frame member and to an extension of one of the movable yarn engaging members aforesaid, said stabilizer functioning to render sluggish responsive movements to the movable members incident to spasmodic variations in the pull upon the yarn.

In testimony whereof, I have hereunto signed my name at 409 Chestnut St., Phila., this thirteenth day of December, 1923.

ANNA M. PIGEON,
Administratrix of the Estate of Albert M. Pigeon, Deceased.
